UNITED STATES PATENT OFFICE.

WARREN B. FLANDERS, OF ESSINGTON, PENNSYLVANIA, ASSIGNOR TO WESTINGHOUSE ELECTRIC AND MANUFACTURING COMPANY, A CORPORATION OF PENNSYLVANIA.

TURBINE BLADE.

1,416,701.

Specification of Letters Patent. Patented May 23, 1922.

Application filed June 22, 1920. Serial No. 390,905.

To all whom it may concern:

Be it known that I, WARREN B. FLANDERS, a citizen of the United States, and a resident of Essington, in the county of Delaware and 5 State of Pennsylvania, have invented a new and useful Improvement in Turbine Blades, of which the following is a specification.

This invention relates to elastic fluid turbines, and more particularly to locking 10 and spacing means for the outer ends of the blades thereof.

It is now common in elastic fluid turbines, in which the blades thereof are arranged in annularly-extending rows, to secure the 15 outer ends of the blades in one such row together by means of a comma-shaped lashing, the tail being sheared on each side of each blade and bent over or turned out of alignment with the comma-shaped holes through 20 the blades, thereby forming spacing pieces which are integral with the locking strip, and the end edges of which contact with the complementary faces of the adjacent blades. The objection to this method is that the end 25 edges of the spacing pieces thus formed do not encounter plane surfaces on the faces of the adjacent blades but the curved surfaces of the blades.

The object of my invention is to provide 30 plane surfaces on the turbine blade where the lashing passes through so that when the tail of the comma-shaped lashing is sheared and bent over, plane surfaces substantially 35 perpendicular to the lashing will serve as abutments for the tail of the lashing.

I attain this object by means of the blade shape shown in the accompanying drawing, in which—

Figure 1 is a plan view of the blade and 40 lashing; Fig. 2, a front elevation of the blade and lashing; and Fig. 3, a sectional view taken along line III—III of Fig. 2.

Referring to the drawing for a more detailed description of my invention, in Fig. 1 45 I indicate a turbine reaction blade 10 formed according to my invention. Near the end of the blade where the lashing 11 passes through, the inner surface of the blade is provided with an indentation or recess 12 so that a plane surface substantially perpendicular to the lashing is formed. On the 50 outer surface of the turbine blade where the lashing passes through an extension or projection 13 is provided which forms a plane 55 surface substantially perpendicular to the

lapping. The portion of the blade where the lashing passes through is therefore of constant thickness and offers plane perpendicular surfaces to the lashing.

In Fig. 2 is shown an elevation of the 60 blade 10 attached to the rotor 14 by any one of the modern methods. The blade at its outer end is provided with a hole or opening 15 conforming to a cross section of the comma-shaped locking and spacing strip 11. 65 These holes or openings are preferably punched in the blades before they are assembled in their holding slots in the rotor, and after a few of the blades have been inserted into the slot the lashing will be 70 threaded therethrough, and the remaining blades strung onto the holding strip and then inserted into the slot in the turbine rotor.

After the blades have been fastened in 75 place in the slot in the turbine rotor and the lashing inserted, the tail 16 of the lashing is cut or sheared in close proximity to the plane surfaces of the indentations 12 and extensions 13 of the adjacent blades, 80 and the tail so sheared is bent over or turned out of alignment with the holes through the blades, thereby forming spacing pieces which are integral with the lashing, and the end edges of which contact with the 85 plane surfaces of the indentations 12 and extensions 13.

Figure 3 a section taken on line III—III of Fig. 2 shows the shape of the blade at the point where the lashing passes through. 90

It is obvious that by forming the blades according to my invention a better connection is obtained between the blades and lashing. In the present method when the lashing is sheared and tail bent over, the 95 end edges encounter the curved surfaces of the blades. By providing a blade as described by my invention, abutments of constant thickness and presenting plane and substantially perpendicular surfaces to the 100 lashing will be formed for the end edges of the sheared lashing.

While I have shown my invention in but one form, it will be obvious to those skilled in the art that it is not so limited, but is 105 susceptible of various other changes and modifications, without departing from the spirit thereof, and I desire, therefore, that only such limitations shall be placed thereupon as are imposed by the prior art or as 110

are specifically set forth in the appended claims.

What I claim is:—

1. A turbine blade having a lashing opening and a lashing member having a deformable tail or tongue portion passing therethrough, a portion of the blade surrounding the opening being of constant thickness to constitute abutments for the deformed tail or tongue portions of the lashing.

2. A turbine blade having a comma-shaped opening and a comma-shaped lashing member in the opening and having the tail portion thereof deformed on each side of the blade, a portion of the blade surrounding the opening being of constant thickness to constitute abutments for the deformed portion of the lashing.

3. The combination of a turbine blade having a comma-shaped lashing opening and plane surfaces surrounding the opening

and substantially normal to the axis of the opening and a comma-shaped lashing member passing through and fitting the opening and having its edge portion deformed adjacent the opening and embracing a portion of said blade of constant thickness defined by said plane surfaces.

4. The combination of a turbine blade having a lashing opening near its tip and plane surfaces on both faces thereof surrounding the lashing opening and substantially perpendicular to the axis of the opening and a lashing member fitting in the opening and partially sheared and deformed on each side of the blade, the blade portion bounded by said plane surfaces constituting an abutment portion of constant thickness for the deformed lashing portions.

In testimony whereof, I have hereunto 40
subscribed my name this 16 day of June, 1920.

WARREN B. FLANDERS.
